RAILWAY TRAFFIC CONTROLLING APPARATUS

George W. Baughman, Edgewood Borough, Pa., assignor to The Union Switch & Signal Company, Swissvale, Pa., a corporation of Pennsylvania

Application February 18, 1928, Serial No. 255,375

97 Claims. (Cl. 246—5)

My invention relates to railway traffic controlling apparatus, and particularly to apparatus adapted for use in a centralized traffic control system for railroads for controlling traffic governing devices from a remote point, such as a dispatcher's office, and for indicating the condition of such devices at said office. More particularly my present invention relates to apparatus of the type described in which the control and indication are effected by means of codes which are transmitted and received by means of relays instead of the usual code transmitting keys and code responsive selectors.

The apparatus of my invention is an improvement upon that disclosed in a copending application for Railway traffic controlling apparatus, Serial No. 254,690, filed Feb. 16, 1928, by Lloyd V. Lewis.

I will describe one form of railway traffic controlling apparatus embodying my invention, and will then point out the novel features thereof in claims.

In the accompanying drawings, Figs. 1 and 2 when arranged with Fig. 1 above Fig. 2, comprise a diagrammatic view showing one form of a portion of the apparatus located at the control office for transmitting control codes. Figs. 3 and 4 when arranged with Fig. 3 above Fig. 4 comprise a diagrammatic view illustrating the equipment located at a field station for receiving control codes from the equipment shown on Figs. 1 and 2 and for also sending codes to the control office. Figs. 5 and 6 when arranged end to end with Fig. 5 on the left comprise a view showing another portion of the office equipment suitable for receiving codes transmitted from the station equipment illustrated on Figs. 3 and 4.

Similar reference characters refer to similar parts in each of the several views.

In general terms the apparatus embodying my invention comprises a normally closed line circuit which includes a source of energy and a plurality of line relays, one located at the control office and one at each station which is controlled from such office. This circuit is at times supplied with different codes by periodically opening and closing the circuit, whereupon the line relays at the office and at all of the stations are periodically energized and de-energized. The system herein illustrated is intended to utilize 4 digit codes, that is, codes made up of 4 groups of units, each unit representing one interruption and reclosing of the line circuit. In the particular form of apparatus here shown, each digit may have any number of units from 1 to 5 and it will therefore

be seen that with 4 digit codes of this type it is possible to provide 625 different codes.

Referring now particularly to Figs. 1 and 2, the reference character OL designates a line relay located at the office and included in a normally closed circuit which also includes line wires 1 and 2 which extend to the stations associated with the apparatus here described. When the apparatus occupies its normal condition in which it is illustrated in the drawings, the master relay 10 OS is de-energized and the transmitter relay OC is energized so that line wire 1 is connected through back contact 3 of relay OS and front contact 4 of relay OC, battery 5 and line relay OL to line wire 2. The reference characters OJ and Od1 designate two relays, the circuits for which are illustrated on Figs. 5 and 6 of the drawings and the operation of which will be described in detail hereinafter. For present purposes, it is sufficient to state that these relays 20 are normally de-energized but are arranged to be energized when a code is being received at the office. The reference character OA designates a slow acting relay which is controlled by a back contact 6 of relay OS, current being supplied to this relay from terminals X and Y of a source of energy not shown in the drawings.

Located at the office is a series of unit relays each designated by the reference character OD with a suitable distinguishing suffix. The office 30 is also provided with a series of digit relays each designated by the reference character OK with a distinguishing exponent. By means of a transfer relay OE the digit relays OK are successively energized by operation of the unit relays OD as 35 will be described in detail hereinafter.

Located also at the office is a line finder designated in general by the reference character F and comprising a stepping magnet 10 which controls a plurality of contact arms 11, 12, 13, 14, 15 40 and 16, each of which co-operates with a plurality of fixed contacts. Associated with the line finder F are a plurality of individual control equipments, one for each station, and only one of which is shown complete in the drawings. This control equipment comprises, in the form here shown, a manually operable switch control lever w having a normal or left-hand position and a reverse or right-hand position. Associated with lever w is 45 a signal control lever r having left-hand, middle and right-hand positions. The levers w and r control a series of start relays each designated by the reference character OH with a distinguishing suffix and a series of stop relays each design- 50 55

nated by the reference character OG with an appropriate suffix.

In explaining the operation of the apparatus shown on Figs. 1 and 2, I will first assume that lever *w* is moved to its reverse position. When this happens, current flows from terminal *X*, over lever *w*, wire 17, back contact 18 of relay OG2, wire 19, and winding of relay OH2 to terminal *Y*. The start relay OH2 therefore becomes energized and closes front contacts 20 and 33. The closing of front contact 29 completes a circuit for the stepping magnet 10 of finder F which may be traced from terminal *X*, over front contact 20 of relay OH2, wire 21, back contact 22 of relay 15 23, wire 24, and winding of magnet 10 to terminal *Y*. Magnet 10 therefore becomes energized to move the armature 25 about the pivot 25^a against the bias exerted by the spring 26. This lifts the pawl 27 out of engagement with the wheel 28 and 20 also closes contact 29. Current then flows from terminal *X*, over front contact 20 of relay OH2, wire 21, winding of relay 23, contact 29, wire 30, and back contact 31 of a relay 32 to terminal *Y*. Relay 23 then becomes energized to open back 25 contact 22 and de-energize magnet 10. The spring 26 then returns armature 25 to its original position, causing the pawl 27 to engage wheel 28 and advance this wheel and the contact arms associated therewith one step. The relay 23 is 30 slightly slow acting and at the expiration of a brief interval of time following the opening of contact 29, back contact 22 of relay 23 closes to re-establish the circuit for magnet 10, thereby causing this magnet to advance the finder another 35 step. This process continues, the contact arms of the finder being advanced in step by step fashion, until the arm 15 engages a contact which is connected with terminal *X*. It will be seen that different contacts associated with arm 15 may be 40 connected with terminal *X* over front contacts of different start relays so that the finder may be stopped in different positions, depending upon the particular one of the start relays OH which is energized. In the present instance, since relay 45 OH2 is energized, when arm 15 engages contact 35 current flows from terminal *X*, over front contact 33 of relay OH2, wire 34, contact 35 and arm 15 of finder F, through winding of relay 32 to terminal *Y*. Relay 32 therefore becomes energized, 50 to open back contact 31 and hold relay 23 de-energized. As a result, the magnet 10 of the finder F is held in its energized condition by relay OH2, and the finder remains at rest in the selected position as long as relay OH2 remains energized. 55 With relay 32 energized, terminal *X* is connected over front contact 36 of this relay and wire 37 with each of the finder arms 11, 12, 13 and 14 so that the contact associated with each of these arms which the arm then engages is connected 60 with the terminal *X*. The finder arms 11 to 14 determine the code to be transmitted, the fixed contacts associated with these finder arms being connected to the vertical line wires shown at the right in Fig. 2 in such a way as to provide a distinctive code combination for each position of the 65 finder switch. In the case described, the code is 2132, in which the first three digits identify the station associated with the individual control equipment shown in Fig. 2, while the fourth digit 70 determines which one of a plurality of possible operations is to be effected at that station. The closing of front contact 36 of relay 32 also completes a circuit through wire 37, back contact 38 of relay OD2 at the top of Fig. 1, thence 75 through back contact 39 of relay OC, and

winding of relay OS to terminal *Y*. Relay OS therefore becomes energized, opening at back contact 3 thereof the normally closed circuit including the line relays at each location. Relay OL therefore becomes de-energized and the line relay at each remaining station becomes de-energized. The opening of back contact 6 of relay OS interrupts the circuit for relay OA but this relay is slow acting and a relatively long interval of time elapses before it closes its back contacts. 10 The breaking of back contact 7 of relay OS de-energized relay OC and this relay now releases. At the expiration of the time required for relay OA to release, the closing of back contact 8 of this relay completes a circuit for relay OC over back 15 contact 9 of relay OB. When relay OA is de-energized, and relay OC is energized, the line circuit is again closed from line wire 1, through front contact 3 of relay OS, back contact 40 of relay OA, and front contact 4 of relay OC. It will be noted 20 however, that with relay OA de-energized, a circuit is completed for relay OB from terminal *X* over back contact 41 of relay OA, wire 42, winding of relay OB, wire 43, front contact 44 of relay OC, wire 45, and back contact 46 of the transfer relay 25 OE to terminal *Y*. Relay OB then becomes energized and breaks at back contact 9 thereon the circuit for relay OC. The release of relay OC interrupts at front contact 44 thereon the circuit just traced for relay OB so that after relay OC 30 drops, relay OB becomes de-energized to re-establish the circuit for relay OC, whereupon relay OB again becomes energized to de-energize relay OC. It will be plain from the foregoing that relay OC will be periodically de-energized and energized to 35 open and close the normally closed line circuit. The first time relay OC becomes de-energized, the first unit relay OD1 is energized over back contact 47 of relay OC. When relay OC next becomes energized the second unit relay OD2 becomes 40 energized over front contact 48 of relay OD1 and front contact 47 of relay OC. When back contact 47 of relay OC next closes, relay OD3 picks up over front contact 49 of relay OD2 and this relay is subsequently stuck 45 up over a circuit which may be traced from terminal *X* over front contact 50 of relay OD2, wires 51, 52 and 53, front contact 54 of relay OD3, and winding of relay OD3 to terminal *Y*. Relays OD1 and OD2 are slow acting, and remain closed 50 during the continued operation of relay OC. This operation continues, each of the unit relays OD being energized in succession by the continued operation of relay OC, until transfer relay OE becomes 55 energized. The circuits are so arranged that relay OE becomes energized when there has been delivered to the line by operation of relay OC sufficient impulses to make up the first digit of the code which it is desired to send. In the present instance the code is determined by the position of 60 the selector arms 11, 12, 13 and 14 on finder F, which now occupy a position corresponding to that in which arm 15 engages contact 35, and it will therefore be seen that when relay OD3 becomes energized, current flows from terminal *X*, 65 over front contact 36 of relay 32, wire 37, contact arm 11 of finder F, and the contact engaged thereby, wires 57 and 58, back contact 59 of relay OK2, wire 60, front contact 61 of relay OD3, wires 62 and 63, and winding of relay OE, to terminal *Y*. 70 Relay OE then becomes energized and is subsequently stuck up by current which flows from terminal *X*, over front contact 50 of relay OD2, wires 51 and 64, front contact 65 of relay OE, wire 66 and winding of relay OE to terminal *Y*. But 75

with relay OE energized, the circuit for relay OB is open at back contact 46 of relay OE, so that when relay OB releases relay OC picks up and remains energized to hold the line circuit closed.

5 When relay OC is energized back contact 47 of this relay is open and after a time interval, relay OD1 drops. The opening of front contact 48 of this relay de-energizes relay OD2 so that this relay also drops. The opening of front contact 50 10 of relay OD2 de-energizes relay OE, and also de-energizes any of the succeeding unit relays OD which may happen to be stuck up. In this case, relay OD3 is the only one energized and this relay now becomes de-energized. It will therefore be 15 plain that in the particular case here described the first digit of the code will be made up of two units at the conclusion of which there is a pause amounting to the time required for releasing relay OD1 plus the release time of relay OD2, plus 20 the release time of relay OE. At the conclusion of this pause, that is, when relay OE becomes de-energized, relay OB again picks up to commence the intermittent operation of relay OC, and to deliver the second digit to the line. The operation 25 of the unit relays delivering the transmission of the second digit is the same as has already been described and will be understood without tracing this operation in detail. It should be pointed out, however, that when relay OE became energized, 30 current was supplied to relay OK1 over front contact 67 of relay OE so that relay OK1 became energized and that this relay was stuck up by current supplied from wire 31 over wire 69 and front contact 70 of relay OK1, through a winding of the relay to terminal Y. Furthermore, when relay OE became de-energized, the closing of back contact 67 picked up relay OK2 over front contact 73 of relay OK1 and relay OK2 is now stuck up over its own front contact 75. It will be seen that 35 with relay OK2 energized, relay OE is controlled by a contact arm 12 of finder F. When the number of impulses have been delivered to the line in accordance with the second digit of the code which is to be sent, relay OE again becomes energized. Since in the code illustrated the second digit comprises but one impulse, this takes place as soon as relay OD1 becomes energized, current then flowing from terminal X, over front contact 36 of relay 32, wire 37, contact arm 12 and the contact associated therewith on finder F, wires 76 40 and 77, back contact 78 of relay OT4, wire 79, front contact 80 of relay OK2, wire 81 and front contact 81a of relay OD1 to wire 63 and thence through winding of relay OE to terminal Y. Relay OE becomes energized then, as soon as relay OC has become de-energized the first time during the second digit of the code. When relay OC next becomes energized, the relay OD2 becomes energized and sticks up relay OE. At the end of the 45 pause introduced by the slow releasing relays OD1 and OD2 the relay OC again begins to operate to send the third digit. The release of relay OD1 de-energizes relay OE, and the operation of relay OE has now picked up, relays OK3 and OK4 in the same manner that relays OK1 and OK2 were 50 picked up at the conclusion of the first digit. In the case illustrated, when relay OD5 becomes energized during the third digit, current flows from terminal X, over front contact 36 of relay 32, wire 37, arm 13 of finder F, wires 82 and 83, back contact 84 of relay OK6, wire 85, front contact 86 of relay OK4, wire 87, front contact 88 of relay OK2, wire 89, front contact 90 of relay OD5, and thence through winding of relay OE to terminal Y. 55 Relay OE sticks up, and serves to introduce the pause between the third and fourth digits. It should be noted that with this arrangement the third digit contains three units. Furthermore, the energization of relay OE to introduce the pause at the end of the third digit picks up relay OK5, and when relay OE again releases it picks up relay OK6, so that at the beginning the last digit of the code, relay OE is de-energized and relay OK6 is energized. When two impulses have been delivered to the line during the fourth digit, current flows from terminal X, over front contact 36 of relay 32, wire 37, arm 14 of finder F, wires 95 and 96, front contact 97 of relay OK6, wire 98, front contact 99 of relay OK4, wire 100, front contact 59 of relay OK2, wire 60, front contact 61 of relay OD3, wires 62 and 63, the winding of relay OE to terminal Y. When this circuit is closed, relay OE becomes energized. Furthermore, the closing of front contact 67 of relay OE completes a circuit from terminal X, over front contact 67, of relay OE wire 68, front contact 101 of relay OK6, and wire 102 to arm 16 to finder F, and thence through wire 103 and winding of stop relay OG2 to terminal Y. Relay OG2 therefore becomes energized to de-energize relay OH2. When relay OH2 drops, magnet 10 of finder F is de-energized and spring 26 restores the armature 25 to the position shown in the drawings, whereupon each of the arms of the finder F are advanced one step to brake the contacts which they previously closed. At the same time, relay 32 is de-energized to disconnect terminal X from wire 37. All of the digit relays OK therefore become de-energized and relay OS also becomes de-energized. Back contact 6 of relay OS closes the circuit for relay OA so that relay OA picks up to remain energized until the next code is transmitted. Back contact 3 of relay OS closes to restore the normal line circuit, and back contact 7 of relay OS completes a circuit for relay OC to hold this relay energized after relay OA becomes energized. Since relay OC now remains steadily energized all of the unit relays return to their de-energized conditions and the apparatus is therefore restored to normal. 30

In the foregoing, it has been assumed that there are no further codes to be transmitted at the time; so that the finder switch will advance one step and then remain in the position corresponding to code 2133. It will be noted, however, that contact 20 of relay OH2 is connected in multiple 35 with the corresponding contacts of all other OH relays, so that if any of these relays have been energized the supply of current to stepping magnet 10 will not be discontinued when relay OH2 releases. Contact 33 of relay OH2, however, controls a circuit that is individual for this relay and therefore when OH2 releases, relay 32 will become deenergized and close its back contact 31, and if current is then supplied to magnet 10, relay 23 will become energized to initiate the stepping action of finder F as already described so that the finder arms will be stepped around until arm 15 reaches a position to close a circuit over a front contact, such as 33, of one of the succeeding OH relays, to again pick up relays 32 and OS to transmit the code which corresponds to the position finder F then occupies. 40

It has already been pointed out that when lever w is moved to its reverse position, the line is supplied with the code 2132. It will be obvious, however, from an examination of the drawings that if the lever w is moved to its normal position, the operation of the apparatus is similar to that just described, but the code delivered to the line will then be 2131, the difference in the last digit being 45

70

75

accomplished by the selection of contacts on the finder F and the consequent change in the control circuits for transfer relay OE. In similar manner, when the left-hand contact of lever r is closed, 5 the code delivered to the line is 2133, when the middle contact of this lever is closed, the code is 2134, and when the right-hand contact lever r is closed, the code 2135 is delivered to the line. These 10 particular codes have been chosen by way of illustration only, and it should be understood that any other four digit codes could be produced depending upon the connections of the finder contacts with the bus bars which connect with the contacts of the digit relays OK.

15 As has been mentioned hereinbefore, the codes supplied to the line circuit in the manner just described operate the line relays at each station in synchronism with the line relay OL at the office. The line relay at each station controls apparatus which is selectively responsive to the code delivered to the line circuit from the office. Referring now to Figs. 3 and 4, it will be seen that the line relay IL is normally included in the series circuit including line wires 1 and 2, this circuit 20 passing from line wire 2 extending to the office, through front contact 104 of relay IC, winding of relay IL, contact 105 operated by relay IS, and thence through line wire 2 to the apparatus at the next station, and so on through each station 25 30 in turn, the line circuit being completed by connecting the outgoing portions of line wires 1 and 2 together at the most remote station. The station equipment, in addition to the relays already mentioned, includes two slow acting relays 1B and 1J 35 and also includes a series of unit relays D and digit relays K.

The apparatus at the station which is selectively responsive to the codes received from the office may be utilized to control governing means 40 of any suitable form. For purposes of illustration, I have shown a section of railway track a—b connected with a siding z by a switch 106 of the usual and well known form. A track relay 1R is connected with the rails adjacent one end 45 of section a—b and a battery 228 is connected across the rails adjacent the other end of the section. Track relay 1R is therefore energized under normal conditions but is de-energized when a train occupies section a—b. The switch 106 is 50 driven by a motor 1M which in the form here shown comprises an armature 112 and a field 111. When switch 106 occupies its normal position, in which it is illustrated in the drawings, contacts 107—107^a, 108—108^a and 109—109^a are 55 closed. When the switch occupies its reverse position, however, the contacts just mentioned, are open, and contacts 107—107^b, 108—108^b and 109—109^b are closed. The switch also controls a contact 110—110^a which is closed at all times 60 except when the switch occupies its reverse position and a contact 110—110^b which is closed at all times except when the switch occupies its normal position. The motor 1M is controlled by two switch control relays 1P and 1Q as will be 65 described in detail hereinafter.

Eastbound traffic over the switch 106 is controlled by a signal t, and westbound traffic over the switch is controlled by two signals u and v, the three signals t, u and v, being controlled by 70 two signal control relays 1T and 1U which are in turn controlled by a trip relay 1V.

In explaining the operation of the station apparatus I will first describe the reception of a code to which the apparatus is responsive, and 75 for example, I will assume that the line is being

supplied with code 2132 as was previously described in connection with the operation of the apparatus located at the office. The first opening of the line during the long time interval required for relay OA at the office to close its back contacts, deenergizes relay IL at the station, thereby energizing the first unit relay 1D1 over back contact 113 of relay IL. The next time relay IL becomes energized, relay 1D2 becomes energized over front contact 113 of relay IL and front 10 contact 114 of relay 1D1. When relay 1D2 picks up, current flows from terminal x, over front contact 116 of relay 1D2, wires 117 and 118, winding of relay 1J to terminal y. Relay 1J is therefore energized as soon as relay 1D2 becomes energized, and due to its slow releasing characteristics, relay 1J remains energized during the pauses between digits in a code, at which times relay 1D2 is de-energized. When relay IL next becomes de-energized, relay 1D3 picks up over front contact 115 of relay 1D2, but relay 1D3 is subsequently held up by current supplied thereto over front contact 116 of relay 1D2, and front contact 119 of relay 1D3. Relay IL then again becomes energized at the conclusion of the second 25 unit of the first digit in the code now being supplied to the line, and then there is a pause before the next operation of relay IL. The energization of relay IL picks up relay 1D4 and this relay is subsequently stuck up over front contact 30 35 40 45 50 55 60 65 70 75 80 85 90 95 100 105 110 115 120 125 130 135 140 145 150 155 160 relay $1L$ picked up relay $1D2$. During the pause between the second and third digits, relay $1D1$ drops and current then is supplied to relay $1K3$ over a circuit which may be traced from terminal x over front contact 120 of relay $1J$, wires 121 and 122 , back contact 123 of relay $1D1$, wire 124 , front contact 125 of relay $1D2$, wire 126 , back contact 127 of relay $1D3$, wires 141 , 142 , and 143 , front contact 144 of relay $1K2$, wire 145 , back contact 146 of relay $1K4$, wire 147 , and winding of relay $1K3$ to terminal y . After relay $1K3$ has picked up, relay $1K4$ is energized as soon as relay $1D2$ opens, and relay $1K4$ is subsequently stuck up over its own front contact 149 and front contact 120 of relay $1J$, relay $1K3$ again becoming de-energized. In similar manner, during the pause at the end of the third digit, since all of the unit relays up to and including relay $1D6$ are now energized, due to the three units in the third digit, a circuit is completed for relay $1K5$ as soon as relay $1D1$ drops. This circuit may be traced from terminal x over front contact 120 of relay $1J$, wires 121 and 122 , back contact 123 of relay $1D1$, wire 124 , front contact 125 of relay $1D2$, wire 126 , front contact 127 of relay $1D3$, wire 128 , front contact 129 of relay $1D5$, wire 150 , back contact 151 of relay $1D7$, wires 152 and 153 , front contact 154 of relay $1K4$, wire 155 , back contact 156 of relay $1K6$, wire 157 , and winding of relay $1K5$ to terminal y . When relay $1D2$ becomes de-energized relay $1K6$ picks up over front contact 158 of relay $1K4$ and is thereafter stuck up over its own front contact 159 and front contact 120 of relay $1J$. Furthermore, the closing of front contact 162 of relay $1K6$ completes a circuit for relay $1K7$, over which current flows from terminal x , over back contact 160 of relay $1S$, wire 161 , front contact 162 of relay $1K6$, and winding of relay $1K7$ to terminal y . With relay $1K7$ energized, an impulse is delivered over one of the front contacts of this relay at the conclusion of the fourth digit. I have assumed that the code being delivered is 2132 and hence when relay $1D1$ drops after the conclusion of the fourth digit, current flows from terminal x , over front contact 120 of relay $1J$, wires 121 and 122 , back contact 123 of relay $1D1$, wire 124 , front contact 125 of relay $1D2$, wire 126 , front contact 127 of relay $1D3$, wire 128 , back contact 129 of relay $1D5$, wires 130 , 163 and 164 , front contact 165 of relay $1K7$, wire 166 , winding of relay $1Q$ to terminal y . Since the code has now been completed, relay $1L$ remains energized and all of the unit relays become de-energized. At the conclusion of the retardation period of relay $1J$, this relay releases and breaks the circuit for digit relays $1K2$, $1K4$ and $1K6$. These relays therefore become de-energized and relay $1K7$ also becomes de-energized to restore the apparatus shown on Fig. 3 to its normal condition. The impulse delivered to relay $1Q$, as described above, energizes this relay, thereby interrupting the stick circuit for relay $1P$ and allowing relay $1P$ to become de-energized. Relay $1Q$ is maintained in its energized condition after the opening of relay $1K7$ by current which flows from terminal x , over back contact 167 of relay $1P$, front contact 168 of relay $1Q$, and a winding of relay $1Q$ to terminal y . When relay $1Q$ becomes energized, a circuit is closed for motor $1M$, operating switch 106 , this circuit passing from terminal x , over front contact 169 of track relay $1R$, wires 170 and 171 , front contact 172 of relay $1Q$, wire 173 , armature 112 of motor $1M$, wire 174 , back contact 175 of relay $1P$, wire 176 , front

contact 177 of relay $1Q$, wire 178 , contact 110 — 110^a operated by switch 106 , and field 111 of motor $1M$ to terminal y . The motor $1M$ is therefore energized to drive the switch 106 to its reverse position. When the switch has attained its full reverse position, contact 110 — 110^a opens to de-energize the motor. It should be observed that if the operator at the control office wishes to restore the switch to its normal position, he may do so by restoring lever w at the office to its normal position, whereupon code 2131 will be delivered to the line and this code will cause operation of relay $1P$ at the station. Relay $1Q$ will then be de-energized and relay $1P$ will be stuck up to complete a circuit for motor $1M$ by means of which the motor will be energized to restore the switch to its normal position in which it is illustrated in the drawings.

In discussing the control of the signals t , u and v , it should be noted that as shown in the drawings, relay $1T$ is energized, by current supplied thereto over back contact 187 of relay $1V$, back contact 189 of relay $1U$, and front contact 188 of relay $1T$. When relay $1T$ is energized, current is supplied to the upper blade of signal t or to the lower blade of this signal according as switch 106 occupies its normal or reverse position. For example, as shown in the drawings, the switch is normal and relay $1T$ is energized, and under these conditions, current flows from terminal x , over front contact 169 of relay $1R$, wires 170 and 190 , front contact 191 of relay $1T$, back contact 192 of relay $1U$, wire 193 , contact 197 — 197^a , wire 194 , and operating mechanism of the upper blade of signal t to terminal y . The remaining signal circuits are similar to that just described and will be obvious from the drawings without tracing them in detail. It should be observed, however, that when relay $1U$ is energized, signal v or signal u is cleared depending upon the position of the switch 106 . If code 2133 is delivered to the station shown in Figs. 3 and 4, relay $1T$ becomes energized and if code 2135 is delivered to this station, relay $1U$ becomes energized. If, however, code 2134 is supplied to the line, the trip relay $1V$ becomes energized, thereby interrupting the stick circuit for which ever one of relays $1T$ or $1U$ is energized, thereby releasing these relays and causing all signals to indicate stop.

It is to be noted that the station apparatus of Figs. 3 and 4 may readily be arranged to receive any of the different station code-combinations which my system employs, by connecting relays $1K1$, $1K3$ and $1K5$ to the group of five vertical bus wires 142 , 131 , etc., according to the code desired which of course is the same as that of the office finder switch for the position associated with the station in question. When the station code connections are arranged as in Fig. 3, it is evident that the station apparatus will fully receive only those codes in which the first three digits are 213, and that when other codes are received, relay $1K7$ will not become energized.

As has been suggested hereinbefore, the equipment illustrated on Figs. 3 and 4 is arranged to permit the transmission of codes to the line circuit for the purpose of actuating indication means in the control office to inform the operator concerning the condition of traffic governing devices located at the station. For purposes of illustration I have arranged the apparatus to give indications in the office concerning the condition of the track section a — b and also concerning the position of the switch 106 .

In explaining this feature of my invention, I

will first assume that the track relay IR becomes de-energized as by the entrance of a train into section $a-b$. When this occurs, back contact 201 of relay IR closes and current flows from terminal x , through back contact 201 of relay IR , wire 202, back contact 203 of relay IG_2 , wire 204, winding of relay IH_2 , wires 205 and 206, back contact 207 of relay IH_3 , wire 208, back contact 209 of relay IH_4 , wire 210, winding of master relay IS at the top of Fig. 3, wire 211, back contact 212 of relay IJ , wire 213, and back contact 214 of relay ID_1 to terminal y . The result of de-energizing relay IR is thus to pick up relay IS , but if the line is in use, this will not occur until the line becomes available because the pickup circuit for relay IS includes back contacts of the slow release relays ID_1 and IJ controlled by line relay IL . When IS picks up, contact 101 is opened, and front contact 217 of relay IS is closed. The opening of contact 105 disconnects that portion of the line wire 2 beyond the station and the closing of contact 217 of relay IS connects the portion of the right-hand terminal of line relay IL directly with line wire 1 so that the line circuit including the office and the station which is about to transmit a code is completed. The closing of front contact 218 of relay IS completes a circuit for relay IB from terminal x , over front contact 218 of relay IS , winding of relay IB , front contact 219 of relay IC , wire 220, back contact 221 of relay IK_1 , wire 222, back contact 223 of relay IK_3 , wire 224, back contact 225 of relay IK_5 , wire 226, and back contact 227 of relay IK_8 to terminal y . Relay IB thereupon becomes energized and interrupts, at back contact 228 thereon, the circuit for the transmitter relay IC , which latter relay then becomes de-energized and opens at front contact 219 thereon, the circuit just traced for relay IB . The opening of relay IC also opens the normally closed line circuit to the dispatcher's office at front contact 104. When relay IC becomes de-energized, relay IB also becomes de-energized, thereby again closing the circuit for relay IC which then becomes energized to pick up relay IB and close the line. It follows therefore that relays IB and IC operate to alternately open and close the line and by properly grouping the impulses thus supplied to the line, indication codes may be obtained of the type to which the apparatus in Figs. 5 and 6 is responsive. The intermittent energization of relay IL picks up the unit relays D in succession, in the same manner as described in connection with the reception of codes at the station. It should be noticed that when relay ID_2 becomes energized, a circuit is closed for relay IJ and that due to the slow acting characteristics of this relay, its front contacts are maintained closed during the intervals that relay ID_2 is de-energized between digits. When relay IJ picks up, wire 211 is disconnected from wire 213 and is connected over front contact 212, wire 215, and front contact 216 of relay IS directly with terminal y , thereby completing a stick circuit for relay IS . When relay ID_1 picked up due to the opening of the line circuit, the circuit of relay IS was opened at back contact 214. Since relay IS is a slow release relay, it remains picked up for the relatively short interval that the line is opened by the operation of relays IB and IC , and as soon as the line is closed and relay IJ picks up, relay IS becomes energized over its stick circuit as just described, and remains energized until relay IJ drops at the end 75 of the code. The operation of relays IB and IC

continues, thereby intermittently operating relay IL , and when relays IC and IL release the second time, relay ID_3 picks up. When this occurs current flows from terminal x , over front contact 160 of relay IS , wire 229, front contact 230 of relay ID_1 , wires 231 and 126, front contact 127 of relay ID_3 , wire 128, back contact 129 of relay ID_5 , wires 130, 131 and 132, back contact 133 of relay IK_2 , wire 134, and winding of relay IK_1 to terminal y so that then 10 relay IK_1 becomes energized. When relay IB releases, relay IC picks up and closes the line, thereby energizing relay IL . A pause now occurs, because the circuit of relay IB is open at back contact 221 of relay IK_1 , so that relay IB 15 remains released and relay IC is held energized. After a time interval, relay ID_1 drops, opening one branch of the circuit for relay IK_1 just traced, but relay IK is now energized over another branch of this circuit which includes front 20 contact 120 of relay IJ , back contact 123 of relay ID_1 and front contact 125 of relay ID_2 . Relay ID_2 now releases, and when relay ID_2 opens its front contact 116, relays ID_3 and ID_4 become de-energized and the closing of back contact 125 25 of relay ID_2 also completes a pick-up circuit for relay IK_2 over front contact 137 of relay IK_1 which pick-up circuit is similar to the circuit previously traced for this relay during the explanation of the operation of the apparatus when a 30 code is being received. Relay IK_2 is subsequently stuck up over its own front contact 140 and front contact 129 of relay IJ , but it should be noted that when the circuit for relay IK_2 is closed, the circuit for relay IK_1 is opened at 35 front contact 125 of relay ID_2 and after relay IK_2 picks up it is maintained open at back contact 133 of relay IK_2 . It follows that relays IK_1 becomes de-energized when relays IK_2 is picked up. After the time interval required for relay 40 IK_1 to drop, the circuit is re-established for relay IB , which thereupon becomes energized and again commences to cause periodic operations of relay IC . In similar manner, during the second digit, relay IK_3 picks up to hold the circuit 45 for relay IB open at its back contact 223, when relay ID_1 becomes de-energized. The circuit for relay IK_3 passes from terminal x , over front contact 160 of relay IS , wire 229, front contact 230 of relay ID_1 , wires 231 and 126, back contact 127 50 of relay ID_3 , wires 141, 142 and 143, front contact 144 of relay IK_2 , wire 145, back contact 146 of relay IK_4 , wire 147 and winding of relay IK_3 to terminal y . After relay IK_3 is energized, relay IK_4 is first picked up and then stuck up and 55 relay IK_3 releases to set relay IB into operation to deliver the third digit. It should be noted that between the beginning and end of the last impulse of a digit, there is interposed the release period of relay ID_1 , plus the release period of 60 relay ID_2 , plus the release period of one of the slow acting relays K and the parts may be so proportioned that the pause thus introduced into the code has the desired time characteristics. At the conclusion of the third digit of the code, 65 relay IK_5 picks up and relay IK_6 subsequently becomes energized and is then stuck up over its own front contact 159 and front contact 120 of relay IJ .

Now if the last digit contains the proper number of units or impulses, an impulse will be delivered at the end of such digit, to pick up relay IK_8 . In the present description I have assumed that relay IH_2 has been energized to deliver code 2132. During the last digit then, after the line 75

relay I_L has been operated to supply two impulses to the line, current flows from terminal x over front contact 160 of relay IS , wire 229, front contact 230 of relay ID_1 , wires 231 and 126, front contact 127 of relay ID_3 , wire 128, back contact 129 of relay ID_5 , wires 130, 163, 232 and 233, front contact 234 of relay IH_2 , wires 235 and 236, front contact 237 of relay IK_6 , wire 238, winding of relay IK_8 to terminal y . Relay IK_8 therefore becomes energized and opens, at back contact 227 thereon, the circuit for relay IB . Relay IK_8 remains stuck up over its own front contact 239 and front contact 120 of relay IJ . But the energization of relay IK_8 also energizes stop relay IG_2 , current flowing from terminal x , over front contact 240 of relay IK_8 , wires 241 and 242, front contact 243 of relay IH_2 , wire 244, and winding of relay IG_2 . After relay IG_2 has become energized, it is stuck up over back contact 201 of relay IR and its own front contact 203. But the opening of back contact 203 of relay IG_2 interrupts the circuit for relay IH_2 and for relay IS , so that both of these relays become de-energized. The opening of relay IS restores the line circuit by closing contact 105. Relay IB is now held open, and relay IC is continuously energized over back contact 228 of relay IB . Relay I_L is therefore continuously energized and all of the unit relays D become de-energized. After a time interval, relay IJ opens, to open the stick circuits for relays IK_2 , IK_4 , IK_6 and IK_8 , whereupon these relays open and restore the apparatus to its normal condition. It should be pointed out that if relay IR becomes energized, the operation of the apparatus will be similar to that just described with the exception that since front contact 245 of relay IH_1 would then be closed, the last digit of the code then supplied to the line would be a single impulse. In similar manner, if the switch 106 is moved to its reverse position, so that contact 109-109^b is closed, relay IH_4 is energized in series with the relay IS , and the code then supplied to the line is 2134. Finally, if the switch is restored to its normal condition to close contact 109-109^a, the energization of relay IH_3 in series with relay IS initiates an operation of the equipment which delivers code 2133 to the line. It will be noticed that the circuits for start relays IH_1 and IH_2 are carried over back contacts on the start relays IH_3 and IH_4 so that if either of the two latter relays is energized, as would be the case when a code corresponding to one of these relays is being delivered to the line, and the condition of track relay IR then changes, neither relay IH_1 nor IH_2 can pick up until both relays IH_3 and IH_4 have returned to their deenergized condition. It is also to be noted that since those portions of the circuits of relays IK_1 , IK_3 and IK_5 which determine the code combination for the station are employed in both sending and receiving, the first three digits of each indication code sent by a station are the same as the first three digits of the control codes which the station receives, the combination being 213 in the example described, as already pointed out.

Referring now to Figs. 5 and 6, these views show a line relay OL which was discussed in connection with Figs. 1 and 2. Relay OS is also shown on Fig. 5. The line relay OL , which is periodically energized and de-energized when a code is being received at the control office, operates a series of unit relays each designated by the reference character d with a prefix O and a

distinguishing suffix. Associated with these unit relays is a series of digit relays each designated by the reference character k with a suitable prefix and suffix, and a plurality of series of register relays e , f and g . The relay OJ is controlled by the second unit relay Od_2 in the same manner that relay IJ is controlled by relay ID_2 in Fig. 3.

Alternate energization or de-energization of the line relay OL picks up the unit relays d in succession. When the first digit has been received, energy is supplied to one of a group of five wires j , depending upon the number of impulses in this first digit. Assuming that the code 2132 is being received, as when a train enters the section $a-b$ in Fig. 4, the first digit of the code comprises two impulses so that after this digit has been received, relays Od_1 , Od_2 , Od_3 and Od_4 are energized. Relay OJ is energized over front contact 254 of relay Od_2 . During the pause following the reception of the first digit, relay OL becomes energized. Relay Od_1 first opens, thereby de-energizing relay Od_2 . During the brief interval that relay Od_2 remains energized due to its slow releasing characteristics, current flows from terminal X , over front contact 256 of relay OJ , wire 257, front contact 258 of relay Od_2 , wires 259, 260 and 261, back contact 262 of relay Od_1 , wire 263, front contact 264 of relay Od_3 , wire 265, back contact 267 of relay Od_5 , wire 268, back contact 269 of relay Ok_2 , wire 270, and winding of relay e_2 to terminal Y . When relay e_2 becomes energized, it is held in this condition over its own front contact 271 and front contact 256 of relay OJ . At the same time that current is supplied to a selected one of a group of wires to pick up a selected one of the group of relays e , current flows from terminal X , over front contact 256 of relay OJ , wire 257, front contact 258 of relay Od_2 , wires 260 and 272, winding of relay Ok_1 to terminal Y . Relay Ok_1 having thus been energized, is stuck up over its own front contact 273 and front contact 256 of relay OJ . When relay Od_2 finally drops during the pause at the end of the first digit, current flows from terminal X , over front contact 256 of relay OJ , wire 257, back contact 258 of relay Od_2 , wires 274 and 275, front contact 276 of relay Ok_1 and winding of relay Ok_2 to terminal Y . Relay Ok_2 therefore becomes energized and is subsequently stuck up over its own front contact 311 and front contact 256 of relay OJ . When the second digit of the code is received by line relay OL , the unit relays Od are successively energized as before, but at the conclusion of this digit, an impulse of energy is supplied to a selected one of a group of wires m , depending upon the number of impulses in such digit. Thus with the code 2132, at the conclusion of the second impulse, after relay Od_1 has released and while relay Od_2 is still picked up, current flows from terminal X over front contact 256 of relay OJ , wire 257, front contact 258 of relay Od_2 , wires 259, 260 and 261, back contact 262 of relay Od_1 , wire 263, back contact 264 of relay Od_3 , wire 279, front contact 280 of relay Ok_2 , wire 281, back contact 282 of relay Ok_4 , wire 283 of group m , and winding of relay f_1 to terminal Y . Relay f_1 therefore becomes energized and is subsequently stuck up over its own front contact 284 and front contact 256 of relay OJ . It will therefore be seen that at the conclusion of the second digit, one of the relays f is energized, depending upon the number of impulses in such digit.

Relays Ok_3 and Ok_4 become energized during

- the pause at the end of the second digit in a manner similar to the energization of relays *Ok1* and *Ok2*. At the conclusion of the third digit, an impulse of energy is supplied to a selected one 5 of a group of wires *n* for picking up a selected one of a group of relays *g*, depending upon the number of impulses in such digit. Since the code now being received has three impulses in its third digit, when relay *Od1* drops at the conclusion 10 of the third digit, current flows from terminal *X*, over front contact 256 of relay *OJ*, wire 257, front contact 258 of relay *Od2*, wires 259, 260 and 261, back contact 262 of relay *Od1*, wire 263, front contact 264 of relay *Od3*, wire 265, 15 front contact 267 of relay *Od5*, wire 288, back contact 289 of relay *Od7*, wire 290, front contact 291 of relay *Ok2*, wire 292, front contact 293 of relay *Ok4*, wire 294, back contact 295 of relay *Ok6*, wire 296 of group *n*, and winding of relay *g3* 20 to terminal *Y*. Relay *g3* therefore becomes energized and is held in this condition by virtue of a stick circuit including its own front contact 297 and front contact 256 of relay *OJ*.

During the pause at the end of the third digit 25 relays *Ok5* and *Ok6* become energized, so that at the conclusion of the fourth digit, an impulse of energy is delivered to a selected one of a group of wires *p* depending upon the number of impulses in such fourth digit. The three groups 30 of relays *e*, *f*, and *g*, corresponding to the first three digits of each code, control a series of relays each designated by the reference character *h* with a distinguishing suffix. The relays *h* are so controlled that for each possible combination 35 of the relays of the first three groups *e*, *f* and *g*, one of the relays *h* will be energized and in the present instance since the first digit was 2, relay *e2* is energized, since the second digit was a 1, the relay *f1* is energized, and since the third digit 40 was a 3, relay *g3* is energized. It will be plain that with these three relays energized, a circuit is completed from terminal *X*, over front contact 277 of relay *e2*, wire 278, front contact 285 of relay *f1*, wires 286 and 287, front contact 298 of relay *g3*, wire 299, winding of relay *h52* to terminal 45 *Y*. Each of the relays *h* has two pair of contacts which are separately connected in multiple with four of the five wires of the group *p*, and each pair of contacts controls a polarized indication relay designated by the reference character *i* with a distinguishing suffix.

At the conclusion of the fourth digit then, after relay *Od1* releases, current flows from terminal *X*, over front contact 256 of relay *OJ*, wire 257, 50 front contact 258 of relay *Od2*, wires 259, 260 and 261, back contact 262 of relay *Od1*, wire 263, front contact 264 of relay *Od3*, wire 265, back contact 267 of relay *Od5*, wire 268, front contact 269 of relay *Ok2*, wire 313, front contact 300 of relay *Ok4*, wire 301, front contact 302 of relay *Ok6*, wire 304 of group *N*, thence through wire 55 305 to front contact 306 of relay *h52*, wire 307, winding of relay *i106* to terminal *Y*. The circuit is closed for only a brief interval, during which 60 the armature of relay *i106* is swung to the right, lighting lamp 308 to indicate to the dispatcher that the section *a-b* shown in Fig. 4 is occupied by a train. Each of the relays *i* is arranged to maintain its contacts in the position to which they 65 70 were last moved so that with the indications obtained by energizing these relays in one direction or the other persists after the energizing circuits for the relays have been opened. After a code has been received, all of the unit relays *d* 75 become de-energized and relay *OJ* also becomes

de-energized. When front contact 256 of relay *OJ* opens, all of the digit relays *k* become de-energized and whichever ones of relays *e*, *f*, *g* and *h* are closed also become de-energized. The apparatus is therefore restored to its normal condition in which it is illustrated in the drawings, except that the indication relays *i* remain in the positions corresponding to the last indication code received. 5

Attention should be drawn to the fact that 10 had the final digit of the code been 1, instead of 2, energy would have been connected with the other winding of relay *i106* over front contact 314 of relay *h52* at the conclusion of the code, and under these conditions lamp 308 would be extinguished. In similar manner, the indication relay *i107* is arranged to indicate to the operator the position of the switch, lamp 309 being energized to indicate that the switch is normal when relay *i107* is energized in one direction, and lamp 20 310 being lighted to indicate that the switch is reversed when the relay *i107* is energized in the opposite direction.

I have described my invention as applied to the control of switches and signals and the return 25 indication of track circuits and switches but this particular arrangement is not essential and has been disclosed solely for purpose of illustration. It should be noted that at the office, the unit relays of the receiving equipment, Fig. 5, are controlled over back contact 249 of relay *OS*, but as has already been described, relay *OS* is energized when the office equipment is sending a code. When a code is being received at the office, relays *OJ* and *Od1* are energized, but back contacts of 30 these two relays are included in series with the operating circuit for relay *OS* which must be energized before the sending equipment at the office shown on Figs. 1 and 2 can be set into operation. It follows that when the office is sending, the receiving equipment at the office is disconnected, and contacts 38 and 39 in the circuit of relay *OS* are prevented from opening. Conversely when a code is being received at the office 35 the sending equipment is disconnected. 40 45

Furthermore, at the station (Figs. 3 and 4) relay *IS* must be energized in order to send a code to the office. But a control can be received at the station only when relay *IS* is de-energized to close back contact 160 for energizing relay *h51* 50 during the last digit of the code. It follows that the sending and receiving equipment at the station cannot interfere.

Moreover, even if two stations start sending at the same time, no interference will occur, because 55 the more remote station will be locked out until the station near the office completes its code, by the operation of contact 105 of relay *IS*. If the office and a station start sending at the same time, the office will take precedence for the following reason: When the line is opened at the office to start a control code, it is held open for a relatively long interval by relay *OA*, as already described. When the line is opened at a station to start an indication code, the periodic operation 60 of relays *1B* and *1C* begins at once so the first opening of the line is relatively short. During this interval the pickup circuit of relay *IS* is open, but its stick circuit is not available until the line becomes closed, and relay *IS*, being a 65 slow release relay, remains picked up if the interval is relatively short, but releases if it is relatively long, as would be the case if the office and station start sending at the same time. In that case, relay *IS* becomes released and the station 70 75 80 85 90 95 98 99 100

apparatus is then in condition to receive the control code and the normal line circuit is also restored so that the code can be received by a more remote station. It follows, therefore, that the station equipments can not interfere with one another nor with the office transmitter.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. Railway traffic controlling apparatus comprising a normally closed line circuit including a source of energy, and a normally closed contact, means for at times periodically opening said contact, a series of relays arranged to be operated in succession when said contact is periodically opened and closed, a traffic governing device, means for stopping operation of said contact in response to the energization of a selected one of said relays, means depending upon the condition of said device for determining which one of said relays is to be selected to stop the operation of said contact, and means controlled by said circuit and selectively responsive to periodic interruptions thereof.

2. Railway traffic controlling apparatus comprising a normally closed line circuit including a source of energy, and a normally closed contact, means for at times periodically opening said contact, a series of unit relays arranged to be operated in succession when said contact is periodically opened and closed, a transfer relay, a series of digit relays controlled by said transfer relay, a traffic governing device means for controlling said transfer relay in response to the energization of a selected one of said unit relays, means controlled in accordance with the condition of said digit relays and the condition of said device for determining which one of said unit relays is to control said transfer relay, and means controlled by the last digit relay in said series for stopping operation of said contact.

3. Railway traffic controlling apparatus comprising a normally closed line circuit including a source of energy, and a normally closed contact, a series of unit relays controlled in cascade, a series of digit relays controlled in cascade, and means controlled by said unit and digit relays for at times periodically opening said contact to supply said circuit with different codes each having a plurality of groups of energy impulses separated by time intervals.

4. In combination, a line relay, means for at times supplying said relay with different codes each having a plurality of digits, a series of unit relays controlled by said line relay and arranged to be operated in succession by successive impulses in each digit of said codes, a plurality of digit relays arranged to become operated progressively as said digits are received by said line relay, a plurality of series of register relays, means controlled by certain of said digit relays for operating a selected one in each series of register relays depending upon the number of units in the corresponding digit of said code, and means controlled by said register relays and selectively responsive to said codes.

5. In combination, a line relay, means for operating said relay intermittently in accordance with a code made up of a plurality of digits each

comprising one or more units, a series of unit relays, means controlled by said line relay for energizing said unit relays successively during each said digit, a series of digit relays, means for energizing said digit relays successively in response to successive digits of said code, and means controlled by said digit relays and selectively responsive to said code.

6. In combination with a line circuit including a transmitting contact, a start relay, a stop relay, means effective only when said stop relay is de-energized for at times energizing said start relay, means effective when said start relay is energized for intermittently operating said transmitting contact to deliver a code to said line circuit, a series of unit relays controlled over said line circuit and arranged to be energized successively in response to intermittent operation of said transmitting contact, means controlled by said unit relays for at times temporarily stopping said transmitting contact to produce a pause between impulses in the code, and means controlled by said unit relays and effective at the conclusion of said code to energize said stop relay to thereby release said start relay.

7. In combination, a line relay, means for operating said line relay in accordance with a code made up of a plurality of digits each having one or more units, a plurality of groups of relays one group for each digit, means controlled by said line relay for energizing a selected relay of said first group depending upon the number of units in the first digit of said code, means for energizing a selected relay in each remaining group at the conclusion of the corresponding digit depending upon the number of units in such corresponding digit, and governing means selectively controlled by the relays of the group corresponding to the last digit.

8. In combination, a line circuit including a transmitting contact, a series of unit relays, means for operating said transmitting contact intermittently to deliver a code to said line circuit, means for energizing said unit relays successively in response to intermittent operation of said contact, means controlled by selected ones of said unit relays for at times stopping said transmitting contact temporarily to introduce a pause in said code and to de-energize all said unit relays, and means controlled by said unit relays for permanently stopping said transmitting contact at the conclusion of a complete code.

9. In combination, a line relay, means for intermittently operating said line relay in accordance with a code made up of a plurality of digits each having one or more units, a series of unit relays, means controlled by said line relay for progressively energizing said unit relays in response to successive units in a digit while permitting all said unit relays to open at the conclusion of each digit, a series of digit relays, means for energizing alternate ones of said digit relays progressively one at the expiration of a time interval following the conclusion of each digit, and means for energizing the remaining digit relays each when the preceding digit relay in the series becomes energized and all said unit relays are open.

10. In combination, a line relay, means for intermittently operating said line relay in accordance with a code made up of a plurality of digits each having one or more units, a series of unit relays, means controlled by said line relay for progressively energizing said unit relays in response to successive units in a digit while per-

- mitting all said unit relays to open at the conclusion of each digit, a series of digit relays, means controlled by a definite one of said unit relays for energizing alternate ones of said digit relays progressively one upon each opening of such definite unit relay, means for energizing the remaining digit relays each when the preceding digit relay in the series is energized and all said unit relays are open, and means effective when any such remaining digit relay becomes closed for holding such relay closed until the completion of said code.
11. In combination, a normally energized line relay, means for intermittently de-energizing said line relay in accordance with a code made up of a plurality of digits each having one or more impulses during which the line relay is open and successive digits being separated by time intervals during which the line relay is closed, a first unit relay arranged to be energized when said line relay is open and having a time element sufficient to bridge the intervals between successive units but not between successive digits of said code, a second unit relay arranged to be energized when said line relay and said first unit relay are both closed, a plurality of other unit relays controlled by said line relay and arranged to be energized progressively by impulses after the first impulse in each digit, a plurality of digit relays, means for energizing alternate ones of said digit relays progressively each one when a predetermined unit relay becomes energized provided the first unit relay then opens, and means for energizing the remaining digit relays each when the preceding relay in the series is energized and all said unit relays are open.
12. In a remote control system, a line circuit, transmitting means for delivering successive code units to said line circuit, a plurality of movable devices, means effective upon a change in the position of any of said devices to initiate operation of said transmitting means, means for at times temporarily stopping said transmitting means to form digits in at least one of which the number of units depends upon which device is operated and in another of which the number of units depends upon the position then occupied by the operated device, and means selectively responsive to the number of units in each digit of a code thus supplied to the line circuit.
13. In a remote control system comprising a line circuit, transmitting means for delivering code elements to said line circuit, a series of unit relays arranged to be operated in succession in response to operation of said transmitting means but to become deenergized if a pause occurs in the operation of said transmitting means, apparatus for at times causing said transmitting means to pause for a brief instant, a group of digit relays, means for operating said digit relays successively in response to successive pauses in the operation of said transmitting means, and means for controlling said transmitting means by said digit relays.
14. In a remote control system comprising a line circuit, transmitting means for delivering code elements to said line circuit, a series of unit relays arranged to be operated in succession in response to operation of said transmitting means but to become deenergized if a pause occurs in the operation of said transmitting means, a movable device, means controlled by said device and by said unit relays for at times causing said transmitting means to pause for a brief instant, a series of digit relays, and means selectively responsive to the unit relays energized at the occurrence of each said pause to operate said digit relays successively.
15. In a remote control system comprising a line circuit, a series of unit relays controlled in cascade, a series of digit relays controlled in cascade and by said unit relays, a different digit relay being operated in response to each operation of one or more of said unit relays, and means controlled by said unit relays and said digit relays for at times transmitting to said line circuit a code made up of groups of energy impulses corresponding to the number of unit relays operated separated by time intervals corresponding to the number of digit relays operated. 15
16. In a remote control system comprising an office and a plurality of stations connected by a line circuit, a single source of energy included in said line circuit at said office, a plurality of line relays one at the office and one at each station and all connected in said line circuit, means at the office for delivering control codes to said line circuit, means at each station controlled by the associated line relay and selectively responsive to said control codes, means at each station for shunting the line at such station through the associated line relay and opening the line to all stations more remote from the office and subsequently transmitting an indication code to the line circuit between such station and the office, and means at the office controlled by the associated line relay and selectively responsive to said indication code. 25
17. A remote control system comprising an office and a plurality of stations connected by a line circuit, a plurality of movable devices at each of said stations; a control panel for each station all located at the office and each including a control lever for each device at the corresponding station, a step-by-step finder switch at said office, means effective when any control lever is actuated to operate said finder switch to a selected position, means controlled by said finder switch when in the selected position to transmit a code message over said line circuit to select the field station associated with the control panel containing said levers and to selectively operate the device corresponding to said lever to a position in agreement with that of said lever, and means controlled by the final element of said message to move said finder switch to a different position. 35
18. In combination, a plurality of contacts, a line circuit, a coding unit adapted to transmit to said line circuit a group of code elements of variable number, means effective when any one of said contacts is operated to actuate said coding unit repeatedly to transmit a plurality of groups of code elements, means controlled by said operated contact for selectively determining the number of code elements in each group to produce a complete code, and receiving means selectively responsive to said complete code. 45
19. A centralized traffic controlling system for railroads, comprising a plurality of contacts, a line circuit, a plurality of coding units for each contact each adapted to transmit to said line circuit a distinctive code element, and means effective when any one of said contacts is operated to actuate each of said units in order to transmit a complete code to said line circuit. 65
20. A centralized traffic controlling system for railroads, comprising a plurality of manually controlled contacts, a stepping contactor, means effective when any one of said contacts is operated to advance said contactor to a selected position. 70

tion, means effective when said contactor occupies said selected position to transmit a distinctive code signal to said line circuit, and means effective when said code signal is completed to advance said contactor to a new position.

21. Code transmitting apparatus comprising a line circuit, a transmitter relay having a contact in said line circuit, a second relay, a pick-up circuit for said transmitter relay including a back contact of said second relay, a circuit for said second relay including a front contact of said transmitter relay, said circuits being thereby adapted to cooperate to actuate said transmitter relay repeatedly to produce a series of impulses in said line circuit, means for energizing said circuits to actuate said transmitter, stepping means controlled by said transmitter relay and adapted to consecutively close a series of contacts, one for each impulse in said line circuit, and means controlled by said last-named means for controlling said transmitter to modify certain ones of said impulses to produce a code.

22. Remote controlling apparatus comprising a line circuit including a line relay, a transmitter relay for interrupting said line circuit, a second relay having a back contact for controlling said transmitter, a circuit for said second relay including a front contact of said line relay, said last-mentioned circuits cooperating to repeatedly actuate said line relay, a series of contacts controlled by said line relay and closed consecutively when said line relay is repeatedly actuated, and means controlled by said contacts for controlling said transmitter to modify certain of said impulses to form a code.

23. A code transmitter comprising a line circuit, a line relay in said circuit, a transmitter relay having a contact in said line circuit, means for periodically energizing said transmitter to repeatedly interrupt said line circuit to actuate said line relay, a series of counting relays energized one at a time in sequence in response to repeated actuation of said line relay, and circuits including contacts of selected ones of said counting relays for stopping said transmitter relay for brief intervals of time to thereby form a code.

24. A code transmitter comprising a line circuit, a line relay in said circuit, a transmitter relay having a contact in said line circuit, means for periodically energizing said transmitter to repeatedly interrupt said line circuit to actuate said line relay, a series of counting relays energized one at a time in sequence in response to repeated actuation of said line relay, a starting circuit for initially energizing said transmitter relay to start the operation of said code transmitter, and circuits including contacts of selected ones of said counting relays and controlled selectively by said starting circuit for stopping said transmitter to prolong selected ones of its periods of energization to thereby form a code.

25. A code transmitter comprising a line circuit, a line relay in said circuit, a transmitter relay having a contact in said line circuit, a master relay, means for actuating said transmitter relay to interrupt said line periodically when said master relay is energized, a series of contacts closed consecutively by repeated operation of said line relay, a series of register relays, means controlled by the contacts of said series and by said register relays for controlling said transmitter to form a code of line signals, means controlled by said code for progressively actuating said register relays in accordance with said code, and means controlled by the last register relay of said series

for registering the completion of said code and for deenergizing said master relay.

26. A code transmitter comprising a line circuit, a line relay in said circuit, a transmitter relay for periodically interrupting said circuit, a master relay, means controlled by said master relay for operating said transmitter relay, a slow release relay controlled by a back contact of said line relay, a second slow release relay controlled by a front contact of said line relay, and means controlled by said slow release relays to release said master relay to stop said transmitter when either of said slow release relays is released.

27. A code transmitter comprising a line circuit, a line relay in said circuit, a transmitter relay for periodically interrupting said circuit, a master relay, means controlled by said master relay for operating said transmitter relay, a first slow release relay controlled by a back contact of said line relay and arranged to release only when said line relay is steadily energized, a second slow release relay controlled by said line relay so as to release only when said line relay is steadily energized or deenergized, a pick-up circuit for said master relay including back contacts of said first slow release relay, and a holding circuit for said master relay including its own front contact and a front contact of said second slow release relay.

28. A code receiver comprising a normally energized line relay, a series of contacts closed consecutively by repeated operation of said line relay in response to a code, a slow release relay controlled by said line relay and deenergized if said line relay remains picked up or released for a period materially longer than the maximum period of an element of said code, a series of register relays each having a circuit closed over one of said consecutively operated contacts provided the corresponding code element is of selected character, and a holding circuit for each register relay controlled over a front contact of said slow release relay.

29. In a remote control system, a line relay, means for deenergizing said line relay repeatedly to produce a code, receiving means effective when operated to respond selectively to said code, a first slow release relay arranged to be energized when said line relay is deenergized, a second slow release relay arranged to be energized when said line relay and said first slow release relay are energized, a third slow release relay arranged to be energized when said first and second slow release relays are energized, means including a back contact of said second slow release relay for operating said receiving means, and means including a front contact of said third slow release relay for maintaining said receiving means in operated condition until the code is completed.

30. A code receiver comprising a line relay; a series of counting relays each except the first controlled over a front contact of a preceding counting relay, alternate relays being controlled also over the front contact, and the remaining relays over the back contact of the line relay; a series of register relays each provided with a circuit including a front contact of a selected counting relay and except in case of the first register relay a front contact of a preceding register relay, and a device controlled by the last register relay of the series.

31. A code relay receiver for receiving a code consisting of a plurality of groups of impulses separated by intervals comprising, a line relay

- operated in accordance with the code, a series of counting relays one for each impulse and interval of a group, a series of group relays one for each group, means for operating the series of counting relays repeatedly in combination with each group relay in turn, and means for selectively registering each group of code impulses including a contact of a counting relay and a contact of a group relay in series.
32. A code relay receiver for receiving a code consisting of a plurality of groups of impulses separated by intervals comprising, a line relay operated in accordance with the code, a series of counting relays one for each impulse and interval of a group, a series of group relays one for each group, means for operating the series of counting relays repeatedly in combination with each group relay in turn, a series of register relays one for each impulse of each group, means for selectively energizing a plurality of register relays over circuits including a contact of a selected counting relay and a contact of each group relay in turn, a plurality of devices, means for selectively operating one of said devices on the last element of a code, said last means including a circuit over closed contacts of each register relay in series.
33. A code relay receiver for receiving a code consisting of a plurality of groups of impulses, comprising a line relay operated in accordance with the code, a series of counting relays controlled by said line relay, a plurality of group relays controlled by said counting relays, means for operating each counting relay a plurality of times each time in combination with a different group relay, a series of register relays for registering the selected impulses of each group which comprise the code, and means for selectively operating said register relays over circuits including contacts of the group relays to determine the group and also including contacts of the counting relays to determine the selected impulse in each group.
34. In a remote control system, station control apparatus comprising a line circuit, a line relay, a series of register relays selectively controlled by said line relay, a movable device, a master relay, a transmitter relay controlled by said master relay, means selectively controlled by said register relays when said line relay is operated by a code signal and said master relay is deenergized to selectively operate said device, means controlled by said device when operated to operate said master relay and transmitter relay to transmit a code signal to said line and thereby actuate said line relay, means controlled by said register relays for controlling the transmitter to selectively determine the code, and means controlled by the final element of said code to deenergize said master relay.
35. A combined code receiver and transmitter comprising a line relay, a series of register relays selectively controlled by said line relay, an operating relay, a series of devices to be operated by received codes, a master relay, a transmitter relay, a release relay, a series of starting contacts for causing codes to be transmitted, means acting in response to a received code for maintaining said master relay deenergized, means controlled by said master relay when deenergized and by the final register relay of said series to actuate said operating relay, means acting in response to the closing of one of said starting contacts to energize said master relay to cause a code to be transmitted, and means controlled by said master

relay when energized and by the final register relay of said series to actuate said release relay, and means controlled by said release relay to open said closed starting contact and thereby release said master relay and stop said transmitter. 5

36. Code signaling apparatus comprising a code receiver connected to a line circuit at a receiving station and arranged to selectively receive a particular code of signals from said line circuit, a transmitter at said station for interrupting said line circuit to transmit a code to the line to actuate said receiver and to also actuate a distant receiver responsive to the same code, means controlled by said first named receiver for governing said transmitter so as to cause said transmitter 15 to generate the particular code to which said receivers are designed to respond, means contained in said first receiver and operated by the final impulse of the code received by said receiver only if said transmitter is then ineffective for selectively operating a device at said station in accordance with the code, and other means contained in said receiver and operated by the final impulse of the code received by said receiver only if said transmitter is then in operation for disconnecting said transmitter. 20

37. A centralized traffic controlling system for railroads comprising a series of counting relays interconnected so that they may be successively energized, a circuit for the first relay including 30 a back contact of the second, circuits for the second and each succeeding even numbered relay each including a front contact of the next preceding relay of the series, a circuit for the third and each succeeding odd numbered relay including a front contact of the next preceding relay and a back contact of the next succeeding relay of the series, the circuits of the odd numbered relays being thereby so arranged that each becomes deenergized when the next succeeding even numbered relay picks up. 35

38. A code transmitter comprising means adapted to create a series of groups of code elements, means for modifying one element in each group to form a code, and means controlled by 45 each modified element to prevent the transmission of any additional elements in the same group.

39. A code transmitter comprising means adapted to create a series of groups of code elements, means for starting said transmitter to 50 transmit a group of elements, means for modifying one element in said group and means controlled by said modified element to prevent the transmission of any additional elements in said group, and to also reset said transmitter to its 55 initial condition to start the transmission of a succeeding group of elements.

40. A code transmitter for generating a code consisting of a plurality of elements of selected character in a line circuit, comprising a transmitter relay for repeatedly interrupting said line circuit, means for controlling said transmitter to cause certain elements to be of selected character and for locking said transmitter to prevent further operation when each of said selected elements is transmitted, line controlled means for registering each of said selected code elements, and means controlled by said last named means and effective when each selected code element is registered to release said locking means to permit 60 said transmitter to continue its operation. 65

41. Code transmitting means for delivering successive code elements to the line wires of a remote control system comprising a transmitting relay, means for operating said transmitting re- 75

- lay intermittently to deliver code elements to said line wires, selecting means for controlling said transmitting relay to impart a selected character to certain of said elements, code registering apparatus selectively responsive to the character of each code element, and means controlled by said code registering apparatus for permitting the transmitter relay to terminate a code element provided the code element transmitted corresponds to the condition of said selecting means.
42. Code transmitting means comprising a transmitter for forming consecutive code elements, means for causing selected code elements to be of a particular character, line controlled means operated by said consecutive code elements, means controlled by said line controlled means for registering each code element of selected character, and means for holding said transmitter on each code element of selected character until such element is registered by said line controlled means.
43. In combination, a line circuit, a transmitter relay for creating a series of code elements in said line circuit, a line relay in said line circuit, a series of contacts arranged to be operated one at a time in sequence in response to repeated operations of said line relay, and means controlled by said contacts for governing said transmitter relay to control the length of each of said code elements.
44. In a dispatching system, a dispatcher's office, a plurality of stations, circuit selecting means at each station, impulse means in the dispatcher's office, a station selecting line circuit, and a series of impulse counting relays at each station governed one at a time in sequence over said line circuit for operatively connecting said impulse means in the dispatcher's office with the circuit selecting means at said stations only one at a time.
45. In a dispatching system, a dispatcher's office, a plurality of stations, selecting means at each station, impulse means in the dispatcher's office, station selecting means for automatically establishing an operative connection between said impulse means and said selecting means at the several stations one at a time in a predetermined sequence, and a manually operable means in the dispatcher's office corresponding with each station for governing the operation of said station selecting means, whereby the stations may be rapidly selected without operating the selecting means except at the station where said manually operable means has been actuated.
46. In a dispatching system, a dispatcher's office, a plurality of stations, selecting means at each station, impulse means in the dispatcher's office, station selecting means in the dispatcher's office operable step-by-step to operatively connect said impulse means to the selecting means at said stations one at a time in turn, means for causing said station selecting means to advance a step after completion of the operation of the selecting means at the corresponding selected station, and manually controllable means for causing said station selecting means to advance from station to station without operating said selecting means.
47. In a dispatching system for railroads, a dispatcher's office, a plurality of way stations, a stepping circuit connecting the dispatcher's office and the several way stations, manually operable means in the dispatcher's office for applying to the stepping circuit any one of a plurality of different code combinations of current impulses, a bank of stepping relays at each station operable sequentially by the impulses of any of said code combinations, code responsive means at each station governed by said bank of relays and selectively responsive to said different code combinations, and means for rendering said code responsive means at the several stations responsive only one station at a time to the code combination of impulses then being applied to the stepping circuit.
48. A remote control system comprising an office and a plurality of stations connected by line wires, a movable device at each said station, a control panel for each station all located at the office and each including a control lever for the device at the corresponding station, a step-by-step finder switch at said office, means effective to operate said finder switch to a selected position, means controlled by said finder switch to transmit a code message to all said stations to select a particular field station and to selectively operate the device at such particular field station to a position in agreement with the corresponding lever at the office, and means controlled by the final element of said message to move said finder switch to a different position.
49. In a centralized traffic controlling system for railroads, a control office and a plurality of field stations, a stepping circuit connecting said control office and said field stations, and step-by-step means at said control office and at each of said field stations operated in synchronism by time-spaced impulses on said stepping circuit irrespective of their character, said step-by-step means including station selecting means responsive only to a particular character of said impulses on said stepping circuit.
50. A selector type system for controlling traffic controlling devices on a railway comprising, a central office, a way station located at a traffic controlling point along the trackway, a coding circuit connecting said office and way station, stepping means for intermittently closing said coding circuit to apply impulses to said circuit, and a code character determining means which if energized allows the application of code impulses of one character and if deenergized allows the application of code impulses of different character by said stepping means, said code character determining means remaining unchanged during the application of a plurality of like successive impulses.
51. A selector type system for controlling traffic controlling devices on a railway comprising, a central office, a way station located at a traffic controlling point along the trackway, a coding circuit connecting said office and way station, stepping means for intermittently closing said coding circuit to apply impulses to said circuit, a normally deenergized system starting relay having a front contact in said circuit, and a code character determining means controlled by said starting relay which if in one condition allows the application of code impulses of one character and if in another condition allows the application of code impulses of a different character by said stepping means, said code character determining means remaining unchanged during the application of a plurality of like successive impulses.
52. In a remote control system of the code type, a starting circuit, means for selectively closing said starting circuit, transmitting means set into operation when said starting circuit is closed for producing successive code elements, receiving means at a remote point normally responding to

said code elements, a second receiving means adjacent said transmitting means normally responding to said code elements, a stopping relay effective when energized to open said starting circuit, and means operating upon the termination of a complete code to energize said stopping relay provided said second receiving means has responded to the last element of said code.

53. In combination, a control station and a receiving station, a movable device and a relay normally occupying positions of agreement, transmitting means at said control station set into operation by a movement of said device out of agreement with said relay for delivering a code 10 made up of a series of code elements of selected characters to said receiving station, means at said control station for registering the characters of certain of said elements during the operation of said transmitting means, and means 15 controlled by said registering means and effective upon the completion of said code to operate said relay into agreement with the new position of said device.

54. In combination, a control station and a receiving station, a movable device and a relay normally occupying positions of agreement, transmitting means at said control station effective when operated to deliver a code made up of a series of code elements of selected characters to 25 said receiving station, said means including stepping apparatus operated progressively by successive elements of said code, means set into operation by a movement of said device out of agreement with said relay for operating said 30 transmitting means, means controlled by said stepping apparatus for registering the characters of certain of said code elements at said control station, and means controlled by said registering means for operating said relay into agreement 35 with the new position of said device.

55. In combination, a control station and a receiving station, a movable device and a relay normally occupying positions of agreement, transmitting means at said control station effective 40 when operated to deliver a code made up of a series of code elements of selected characters to said receiving station, said means including stepping apparatus operated progressively by successive elements of said code, means set into operation by a movement of said device out of agreement with said relay for operating said transmitting means, a group of registering relays at said control station, means controlled by said stepping apparatus for selectively energizing certain of 45 said registering relays during the delivery of a code in accordance with the characters of certain elements of such code, means for subsequently holding such selected registering relays energized until the completion of the code, and means controlled by said registering relays for operating 50 said relay into agreement with the new position of said device.

56. In combination with a normally closed line circuit including a line relay, a slow release relay 55 arranged to become released if said line relay remains energized for more than a predetermined time, a chain of counting relays, means effective only if said slow release relay remains picked up for operating the relays of said chain progressively when said line relay is operated repeatedly, and means controlled by said counting chain for repeatedly opening said line circuit in accordance with a predetermined code to operate said line relay.

57. In combination with a normally closed line

circuit including a line relay, a slow release relay arranged to become released if said line relay remains energized for more than a predetermined time, a second slow release relay arranged to become released if said line relay or said slow release relay remains deenergized for more than a predetermined time, a chain of counting relays, means effective only if said second slow releasing relay remains picked up for operating the relays of said chain progressively when said line relay is operated repeatedly, and means controlled by said counting relays for repeatedly opening said line circuit in accordance with a predetermined code to operate said line relay.

58. In combination with a line circuit including a line relay, a slow release relay arranged to become energized when said line relay is operated, means for releasing said slow release relay if said line relay remains energized or remains deenergized for more than a predetermined time, transmitting means adapted to repeatedly interrupt said line circuit to transmit a code over said line circuit, means effective only when said slow release relay is deenergized to initiate the operation of said transmitting means, and means effective only if said slow release relay becomes energized to complete the operation of said transmitting means.

59. In combination with a normally closed line circuit including a line relay, means for repeatedly opening said line circuit to produce a distinctive code, a first slow release relay arranged to become released if said line relay remains energized for more than a predetermined time, a second slow release relay arranged to become released if said line relay or said first slow release relay remain deenergized for more than a predetermined time, a chain of counting relays, means controlled by said line relay in response to said code and effective only if said second slow release 40 relay remains picked up to operate the relays of said counting chain progressively, and receiving means controlled by said counting chain and selectively responsive to said code.

60. In combination with a line circuit including a line relay adapted to receive code impulses, a slow release relay arranged to become energized when said line relay is operated, means for releasing said slow release relay if said line relay remains energized or remains deenergized for more than a predetermined time, a chain of counting relays, means for operating the relays of said chain progressively when said line relay is operated repeatedly by the impulses of a code, provided said slow release relay remains picked 55 up, and code receiving means controlled by said counting relays.

61. A combined code receiver and transmitter for a remote control system having a line circuit at times supplied with a code of time spaced impulses, a master relay, a transmitter for repeatedly interrupting the line circuit, a line relay in said line circuit, a series of contacts closed sequentially as said line relay is operated repeatedly, a register relay, means for picking up said 60 register relay only when a selected contact of said series becomes closed, means rendered effective when said master relay is picked up to set said transmitter into operation, means rendered effective when said register relay picks up to 65 temporarily interrupt the operation of said transmitter to produce a pause in the code, means effective if said master relay is deenergized to prevent said register relay from picking up when the selected contact of said series becomes closed 70 75

unless a pause then occurs in the code, a movable device, means for selectively operating said device if the register relay is picked up during a received code when the master relay is deenergized, 5 and means for at times energizing the master relay to transmit a code.

62. A combined code receiver and transmitter for a remote control system having a line circuit at times supplied with a code of time spaced 10 pulses, a master relay, a transmitter for repeatedly interrupting the line circuit, a line relay in said line circuit, a series of contacts closed sequentially as said line relay is operated repeatedly, a register relay, means for picking up said register relay only when a selected contact of said series becomes closed, means rendered effective when said master relay is picked up to set said transmitter into operation, a first slow release relay arranged to release when a pause occurs in a 20 code, a second slow release relay controlled by said first slow release relay, means rendered effective when said register relay picks up for stopping the operation of said transmitter until both of said slow release relays become released, and 25 means for receiving a code from said line circuit comprising means effective when the master relay is deenergized for preventing said register relay from picking up when the selected chain relay is operated unless a pause then occurs in the 30 code to cause said first slow release relay to release.

63. In combination with a line circuit including a line relay, transmitting means effective when operated to repeatedly open and close said 35 line circuit to produce a code, a first slow release relay arranged to be energized when said line relay is deenergized during said code, a second slow release relay arranged to be energized when said line relay is energized during said code, and a circuit closed only when both said slow release relays are deenergized for initiating the operation of said transmitting means.

64. In combination with a control office and a plurality of stations, a line circuit extending from 40 said office through all said stations in series, transmitting means at each station including a line relay in the portion of the line circuit extending from the office to such station for delivering codes originating at such station to the 45 office, a first slow release relay at each station controlled by a back contact of said line relay, a second slow release relay at each station controlled by a front contact of said line relay and by said first relay, means effective only when both 50 slow release relays have been deenergized for a predetermined time to initiate operation of the associated transmitting means, and means for subsequently continuing the operation of said transmitting means to deliver a complete code to the line circuit only if said second relay becomes 55 energized.

65. In combination with a control office and a station, a normally closed line circuit extending from the office to said station and including a line relay at said station, a master relay at the 60 station, transmitting means arranged to be operated when the master relay is energized for delivering codes originating at the station to the office, a first slow release relay controlled by a back contact of said line relay, a second slow release relay controlled by front contacts of said line relay and of said first slow release relay, a pickup circuit for said master relay controlled by back contacts of said slow release relays and arranged to be closed only when the line relay has 65

been steadily energized for a predetermined time, and a stick circuit for said master relay controlled by a front contact of said second slow release relay and arranged to become closed in response to the operation of the line relay by a code 5 and to be opened in the event the line relay is deenergized and fails to pick up for a predetermined time.

66. A train dispatching system of the synchronous selector type comprising, a dispatcher's 10 office, a plurality of way stations, synchronous selector means at said dispatcher's office and at each of said way stations, a plurality of circuit branches for each of said selectors, operating means for operating said selectors in synchronism 15 for causing sequential closure of corresponding circuit branches of said selectors in synchronism, said operating means operating said selectors step by step at a predetermined rate, and supplemental means for causing certain steps in the 20 operation of said synchronous selectors to be taken at a predetermined slower rate.

67. In a centralized traffic controlling system for railroads, a control office, a plurality of field stations, two line wires constituting a stepping 25 circuit extending from the control office through the several stations, step-by-step means at the control office and at each of said stations operated synchronously by impulses on said stepping circuit, traffic controlling devices at each 30 station, control levers in the control office for the traffic controlling devices at each station, means controlled by the control levers and the step-by-step means in the control office for applying different code combinations of impulses 35 to said stepping circuit, and means at each station controlled by the step-by-step means at such station and responsive to different code combinations of current impulses applied to said stepping circuit for selecting one of said stations and 40 governing the operation of a traffic controlling device at that station in accordance with the position of the corresponding control lever.

68. In a centralized traffic controlling system for railroads, a control office, a plurality of field 45 stations, a stepping circuit extending from the control office through the several stations, a plurality of traffic controlling devices at each station, governing means at each station for controlling the traffic controlling devices at that station in accordance with impulses on said stepping circuit, and means manually controllable by the operator and acting over said stepping circuit alone for rendering said governing means at said stations responsive only one at a time to the impulses thereafter applied to said stepping circuit.

69. In a centralized traffic controlling system for railroads, a control office, a plurality of field stations, a stepping circuit, step-by-step means at the control office and at each field station all operated in synchronism by impulses on said stepping circuit irrespective of their character, means controlled by the step-by-step means at the control office for applying impulses of distinctive character to said stepping circuit, and station selecting means at each station controlled by the step-by-step means at such station and selectively responsive to the character of the impulses applied to said stepping circuit.

70. In a centralized traffic control system for railroads, a plurality of field stations, a control office, a line circuit connecting said control office with said field stations, a plurality of control 75

lever divided into groups corresponding to the stations, means for impulsing said line circuit with a plurality of series of impulses of distinctive character, code determining means associated with each group of control levers for determining, when actuated, the character of each impulse of any one series, and automatic means causing only one of said code determining means to be effective during the transmission of any one series of impulses irrespective of the number of said code determining means which are actuated at any one time.

71. In a centralized traffic control system for railroads, the combination with a plurality of field stations, of a control office, a line circuit connecting said control office with said field stations, a plurality of control levers divided into groups corresponding to the stations, code determining means associated with each group of control levers, means for impulsing said line circuit with a plurality of series of impulses with each impulse of a series having any one of a plurality of distinctive characteristics in accordance with a particular one of said code determining means, and means allowing only one of said code determining means to be effective during the transmission of any one series of impulses irrespective of the number of said code determining means which are actuated at any one time.

72. In a centralized traffic controlling system, a control office, a plurality of field stations, a line circuit connecting said control office with said field stations, code circuits connected by jumper wires in various combinations at each of said field stations, station selecting means at each field station, an impulse relay, and a holding relay controlled over said line circuit, means including a contact of said impulse relay and a contact of said holding relay for initiating the operation of said station selecting means at each station for a cycle of operation, means controlled by a particular code circuit combination at each station for continuing the operation of said station selecting means at that station throughout a cycle of operation, and means effected by changing a single one of said jumper wires at a station for changing the code circuit combination required for continuing the operation of said station selecting means at that station during a cycle of operation.

73. In a dispatching system, a plurality of stations, traffic controlling devices at each station, a bank of neutral relays at each station for establishing when operated sequentially a series of separate channel circuits for the control of said traffic controlling devices at that station, a dispatcher's office, and means for automatically operating sequentially the relays of the banks at said stations from the dispatcher's office only one bank at a time, whereby the channel circuits are established only at one station at a time.

74. In a dispatching system, a dispatcher's office, a plurality of stations, a bank of channel circuit selecting relays at each station, station selecting means for causing complete operation of said banks of relays at the several stations only one at a time, manually operable levers in the dispatcher's office for each station, and means responsive to a change in the position of the levers associated with each station for governing the operation of said station selecting means.

75. In a dispatching system for railroads, a dispatcher's office, a plurality of way stations, a stepping circuit connecting the dispatcher's office with the several way stations, means for ener-

gizing said stepping circuit with a plurality of impulses, a bank of neutral stepping relays at each station each stepping relay having a pick-up circuit controlled by the front contact of the next preceding relay in the bank, means controlled by the impulses on said stepping circuit for alternately energizing the pick-up circuits for alternate stepping relays of said bank, and stick circuits for each of said relays closed until the application of the last impulse of said plurality of impulses.

76. In a centralized traffic control system, means for transmitting indications from a field station to a control office over a single line circuit comprising, step-by-step means in the control office and at the field station operated synchronously by impulses on said line circuit, a group of two-position polar relays in the control office having contacts which stay where positioned by each energization until changed by an energization of the opposite polarity, energizing circuits for said relays selectively controlled by said step-by-step means, means for supplying current to said energizing circuits to energize said relays in one direction or the other in accordance with the time duration of energization of said line circuit, and means at the field station governed by the step-by-step means thereof for varying the time duration of certain of the impulses in accordance with the indications to be transmitted.

77. In a centralized traffic control system, the combination with a single line circuit intermittently energized with impulses of variable duration, a plurality of polar relays having contacts which stay where put, means responsive to the energizations and deenergizations of said line circuit irrespective of their duration for establishing energizing circuits for said relays, and means including two slow acting relays which are respectively conditioned in accordance with the duration of energization and deenergization of said line circuits for supplying current to said circuits to operate said relays to one position or another.

78. In a code signaling system, means for transmitting multiple element codes from any one of a plurality of stations to a control office, comprising a code receiver at each station connected to a line circuit leading to said office, each said receiver being selectively responsive to a code in said line circuit to which none of the other receivers is responsive, a receiver at said office selectively responsive to each of said codes, code generating means at each station effective when set into operation to initiate the transmission to the line circuit of that code to which the associated receiver is responsive, and means effective only when such receiver responds to said code for continuing the operation of said code generating means to complete the code.

79. In a code signaling system, means for transmitting multiple element codes from any one of a plurality of stations to a control office, comprising a code receiver at each station connected to a line circuit leading to said office, each said receiver being selectively responsive to a particular sequence of code elements in said line circuit, a receiver at said office selectively responsive to each such sequence of code elements, code generating means at each station effective when set into operation to initiate the transmission to the line circuit of that sequence of code elements to which the associated receiver is responsive, and means rendered effective by the re-

sponse of said receiver to each code element in turn for continuing the operation of said code generating means to transmit the next succeeding code element of the sequence following the one to which the receiver responds.

80. In combination with a plurality of stations connected by a line circuit, a movable device at each station, a transmitter relay at each station set into operation upon a change in condition of the movable device at such station to create a series of code elements in said line circuit, each said series identifying a particular station, a line relay at each station in said line circuit, a selector relay at each station selectively responsive to the operation of said line relay in accordance with the particular series of code elements for such station, and means controlled by said selector relay for governing the associated transmitter relay.

81. In combination with a plurality of stations connected by a line circuit, a movable device at each station, a transmitter relay at each station set into operation upon a change in condition of the movable device at such station to create a series of code elements in said line circuit, said elements being arranged in two groups, the first of which identifies the transmitting station and the second of which identifies the condition of the movable device at such station, a line relay at each station included in said line circuit, a selector relay at each station selectively responsive to the operation of said line relay in accordance with the first group of elements of a series, provided such group fully identifies the corresponding station, and means dependent upon the response of said selector relay to said first group of elements for continuing the operation of the transmitter to create the second group of elements of the series in accordance with the condition of the movable device.

82. In a code signaling system, an office and a plurality of stations, a code receiver at each station, each including manually adjustable circuit connections so arranged that the receiver is rendered selectively responsive to a code to which none of the other station receivers is responsive, a receiver at the office selectively responsive to each of said codes, manually controlled code transmitting means at the office for generating codes to selectively operate said station receivers, starting means at each station for setting the associated receiver into operation, and code transmitting means controlled by each station receiver when set into operation by such starting means for generating the code to which such receiver is responsive to operate the receiver at the office.

83. In a remote control system, an office and a plurality of stations, a movable device at each station, a code transmitter at each station set into operation upon a change in condition of the movable device at such station to generate a multiple element code, means including adjustable circuit connections for governing the character of said code, a receiver at the office responsive to said code, a manually controlled transmitter at the office adapted to transmit a plurality of different codes, a selector relay at each station, means including the adjustable circuit connections of the associated transmitter for rendering said selector relay selectively responsive to a particular code, and means controlled by said selector relay for operating the associated movable device.

84. In a centralized traffic controlling system for railroads, a dispatcher's panel having a plurality of keys each corresponding to a distant

track signal for governing traffic over the associated track sections, code transmitting apparatus common to all said keys for transmitting codes each comprising a plurality of series of pulses, a plurality of stop code conductors for determining the number of pulses in each series of a transmitted code, means for successively marking one of said conductors for each successive series of pulses in a code to be transmitted in accordance with the operation of one of said keys, means in said coding apparatus for successively connecting with said conductors for each series of pulses to be transmitted in response to the operation of said key, means for stepping further successive connections to said conductors for each series in response to connection with a marked conductor, means in said coding apparatus for transmitting a pulse for each said successive connection whereby said stopping means divides the pulses transmitted into series of pulses comprising a code, and means controlled by the transmitted code for operating the track signal in accordance with the operated key.

85. In a code transmitter for use in a centralized traffic controlling system for railroads, a pulse sender, a group of digit stop conductors, a first digit stop relay, means for connecting said first digit stop relay to a particular stop conductor, means for operating said sender to transmit pulses and at the same time successively connect with said stop conductors, means for operating the first digit stop relay in response to the connection of the sender with said particular stop conductor to terminate said transmission of pulses for the first digit, a second digit stop relay, means responsive to the operation of said first digit stop relay for connecting said second stop digit relay to one of said stop conductors and for reoperating said sender to again transmit pulses and successively connect with said stop conductors, means for operating said second digit stop relay in response to the connection of the sender with said one conductor to terminate said transmission of pulses for the second digit, a third digit stop relay, means responsive to the operation of said second digit stop relay for marking one of said stop conductors and for reoperating said sender to again transmit pulses, said last reoperation of said sender successively connecting said third digit stop relay to said stop conductors, and means for operating said third digit stop relay in response to the completion of the circuit of said relay with said marked conductor to terminate said transmission for the third digit.

86. In a centralized traffic controlling system for railroads, a field station, a combined receiver and transmitter in said station, means for transmitting a code comprising a plurality of digits to said combined receiver and transmitter, a group of counting relays in said combined receiver and transmitter, means for successively operating said relays to count the number of pulses for each digit of the received code, means for operating the combined receiver and transmitter to transmit a like code comprising a plurality of digits from said field station, means for successively operating said relays for each digit to count the number of pulses in each digit of the transmitted code, and operating circuits successively completed in response to the last counting relay operated for each digit for selecting and operating a device in accordance with the digits received and for determining the number of pulses in each digit transmitted therefrom.

87. In a centralized traffic controlling system

for railroads, a field station, a combined receiver and transmitter in said station, means for transmitting a code comprising a plurality of digits to said combined receiver and transmitter, a counting device in said combined receiver and transmitter operated for counting the number of pulses in each digit of the received code, means for operating said combined receiver and transmitter to transmit a like code comprising a plurality of digits from said field station, and means for operating said counting device to count and determine the number of pulses in each digit of the transmitted code.

88. In a centralized traffic controlling system for railroads, a field station having a plurality of track signals for governing train traffic over associated track sections, position control relays for controlling said track signals, a set of counting relays in said field station, means for transmitting a code to said field station, said code comprising three digits and each digit including a plurality of pulses, means for reoperating said counting relays for each transmitted digit of said code, said counting relays sequentially operated whereby one counting relay is operated for each pulse of the code, an individual conductor for each counting relay, a common conductor sequentially connected to each individual conductor by the sequential operation of said counting relays for each digit of said code, a source of current, means for connecting said source to said common conductor and to the connected individual conductor of the counting relay last operated in response to the termination of each transmitted digit of said code, a first relay operated by the connection of said source to said common conductor over the connected individual conductor of the counting relay last operated for the first digit, a second relay controlled by said first relay and operated by the connection of said source to said common conductor over the connected individual conductor of the counting relay last operated for the second digit, means responsive to the operation of said second relay for connecting said individual conductors to said position control relays, a particular one of said position control relays operated by the connection of said source to said common conductor over the connected individual conductor of the counting relay last operated for the third digit, and means controlled by the operated position control relay for operating the track signal corresponding to the transmitted code.

89. In a centralized traffic controlling system for railroads, a dispatcher's station, a plurality of field stations connected in tandem to said dispatcher's station, means for transmitting codes from said dispatcher's station to all said field stations, each code comprising three digits and each digit comprising a variable number of pulses, a plurality of track signals associated with each field station for governing train traffic over associated track sections, position control relays in each field station for controlling said track signals, a set of counting relays in each field station, means for reoperating said counting relays for each digit transmitted from the dispatcher's station and said counting relays sequentially operated whereby one relay is operated for each pulse received, an individual conductor for each counting relay, a common conductor in each field station sequentially connected to each individual conductor by the sequential operation of the associated counting relays for each transmitted digit, a source of current at

each field station, means at each field station for connecting said source to the common conductor thereat and to the connected individual conductor of the counting relay last operated in response to the termination of each transmitted digit, a first digit relay at one of said field stations operated by the connection of said source to said common conductor thereat over the connected individual conductor of the counting relay last operated for the first digit, a second digit relay at said one field station controlled by said first digit relay and operated by the connection of said source to said common conductor thereat over the connected individual conductor of the counting relay last operated for the second digit, means responsive to the operation of said second digit relay for connecting said individual conductors of said one field station to the associated position control relays, a particular one of said position control relays at said one field station operated by the connection of said source to said common conductor thereat over the connected individual conductor of the counting relay last operated for the third digit, and means controlled by the operated position control relay for operating the track signal corresponding to the transmitted code.

90. In combination; line wires having a plurality of different series of distinctive impulses applied thereto; a bank of stepping relays; means for operating all of said relays in said bank sequentially for any series of impulses applied to said line circuit; a channel circuit prepared by each of said stepping relays when it is operated; control means for branching certain of said channel circuits into any selected one of a plurality of branches; and means governing said control means to select particular ones of said branches for any particular operation depending upon the particular series of distinctive impulses which is causing such operation.

91. In combination, a sending station and at least one receiving station, a bank of stepping relays at the receiving station and operatively connected to the sending station, means for operating the stepping relays from the sending station one at a time, a plurality of channel circuits prepared by said relays, said channel circuits including group and station channel circuits, the station channel circuits for connecting the group channel circuits to the sending station, and the group channel circuits each for connecting a group of devices at the receiving station to the sending station by way of the station channel circuits, and means selectively controlled for completing a station selecting channel and a group selecting channel of the selected station channel.

92. In combination, a sending station and at least one receiving station, a bank of stepping relays at the receiving station and operably connected to the sending station, means for operating the stepping relays from the sending station one at a time, a plurality of channel circuits prepared by said relays, said channel circuits including group and station channel circuits, the station channel circuits for connecting the group channel circuits to the sending station, and the group channel circuits each for connecting a group of devices at the receiving station to the sending station by way of the station channel circuits, and means at the sending station selectively controlled for completing a station selecting channel and a group selecting channel of the selected station channel.

93. In combination, a sending station and at least one receiving station, a bank of stepping relays at the receiving station and operably connected to the sending station, means for operating the stepping relays from the sending station one at a time, a plurality of channel circuits prepared by said relays, said channel circuits including group and station channel circuits, the station channel circuits for connecting the group channel circuits to the sending station, and the group channel circuits each for connecting a group of devices at the receiving station to the sending station by way of the station channel circuits, and means at the receiving station selectively controlled for completing a station selecting channel and a group selecting channel of the selected station channel.

94. In combination; a line circuit having a plurality of different series of distinctive impulses applied thereto; a bank of stepping relays; means for operating all of said relays in said bank sequentially for any series of impulses applied to said line circuit; a channel circuit prepared by each of said stepping relays when it is operated; control means for branching certain of said channel circuits into any selected one of a plurality of branches; and means governing said control means to select particular ones of said branches for any particular operation depending upon the particular series of distinctive impulses which is causing such operation.

95. In combination; a bank of stepping relays; means for operating all of said relays of said bank sequentially; a plurality of groups of channel circuits prepared by said bank of stepping relays, one group for each operation of said stepping relays, each such group comprising a circuit path divided into a plurality of branches; and means remotely controlled prior to the preparation of said groups of channel circuits for selecting for use during any particular operation of

said bank of stepping relays only a particular branch of each of said groups of channel circuits.

96. In combination; a bank of stepping relays; means for operating all of said relays of said bank sequentially; a plurality of groups of channel circuits prepared by said bank of stepping relays, one group for each operation of said stepping relays, each such group comprising a circuit path divided into a plurality of branches; and means manually governed from a remote point for selecting prior to the preparation of each group of channel circuits which branch for that group of channel circuits shall be closed during the corresponding operation of said bank of stepping relays.

97. A code signaling device comprising a transmitter adapted to produce a series of code signal elements in a line circuit, certain ones of which are of a particular character, a receiver associated therewith including a line relay adapted to receive code signals from said line circuit including those signals produced by said transmitter; a series of contacts closed one at a time in sequence in response to repeated operation of said line relay, a plurality of adjustable circuit portions, each of which is adapted to be connected to certain ones of said contacts, transmitting circuits including said circuit portions and the contacts to which they are connected for causing selected code elements to have a particular character, and receiving circuits including said circuit portions and the same ones of said series of contacts for operating receiving stick relays when the selected code elements have said particular character, whereby said code signaling device may be readily adapted to send and receive any one of a plurality of code signals by connecting said circuit portions to different ones of said contacts.

GEORGE W. BAUGHMAN. 40
